UNITED STATES PATENT OFFICE

CHARLES VAN DYKE HILL, OF ST. LOUIS, MISSOURI.

ELECTRICAL SAD-IRON HEATER.

No. 853,694.

Specification of Letters Patent.

Patented May 14, 1907.

Application filed September 15, 1906. Serial No. 334,700.

To all whom it may concern:

Be it known that I, CHARLES VAN DYKE HILL, a citizen of the United States, residing in the city of St. Louis, in the State of Missouri, have invented certain new and useful improvements in Electrical Sad-Iron Heaters, of which the following is a full, clear, and exact description, reference being had to the accompanying drawings forming part of this specification.

My invention relates to an electrical heater so constructed as to be susceptible of having an ordinary sad-iron mounted thereon and having means associated therewith whereby the sad-iron may be secured to the heater, the heater being further so constructed as to constitute the ironing member whereby the ironing may be accomplished by the heater and an ordinary sad-iron be of utility for the purpose of providing the necessary weight and a handle for the manipulation of the iron.

Figure I is a perspective view of my heater and an ordinary sad-iron clamped thereto. Fig. II is a top or plan view of the heater with its top plate omitted. Fig. III is a vertical longitudinal section taken through the heater and its clamping means and showing the sad-iron mounted on said heater in elevation.

1 A designates an ordinary sad-iron which is provided with the handle B.

1 I designates the body of my heater which is of recessed form and has a smooth ironing surface at its bottom. The heater body is surmounted by a top plate 2 that closes the cavity in the heater body and constitutes a bed for the sad-iron A.

1 3 designates a core of insulation material 40 that is positioned in the cavity of the heater body and on which is wrapped a resistance wire 4. The core 3 as herein shown is of approximately triangular shape and the resistance wire is shown as being wound around 45 said core and seated in notches therein. The construction of the core and the manner of winding the resistance wire do not, however, constitute any part of my present improvement, and no invention *per se* is herein claimed 50 for them. The ends of the resistance wire are connected to cords 5 that lead from the interior of the heater body to its exterior and may be connected by any suitable means with a source of electrical energy.

6 designates binding rods seated in the 55 heater body 1 and extending vertically therefrom. These rods are threaded and have fitted thereto nuts 7, preferably of winged type.

8 is a clamping bar that is perforated adjacent to its ends and is adapted to be fitted to the binding rods 6. This clamping bar extends transversely across the heater body and its top plate, and is adapted to rest on the body of the sad-iron A when said iron is 65 seated on the electrical heater, in which position the clamping bar serves to hold the sad-iron body firmly to the heater when the binding rod nuts are in a tightened condition. It will be seen that the sad-iron may be very 70 firmly attached to the electrical heater by the described parts and that when the parts are so attached the sad-iron and the heater beneath it may be manipulated with ease and readiness in ironing operations, the heater 75 serving the double function of a carrier for the heating unit associated therewith and of an ironing or smoothing member, while the sad-iron serves to afford the requisite weight necessary for satisfactory ironing operation 80 and the handle portion for the manipulation of the parts.

While I have shown and described only one means for attaching the sad-iron to the electrical heater, it is obvious that other 85 means for attaching the parts together may be employed, and I therefore do not wish to be limited to the particular form of means for attaching described.

A sad-iron heater constructed as herein 90 described may be very inexpensively manufactured, due to its simplicity and the fact that it may be made of less weight than strictly electrical sad-irons are ordinarily made, this being due to the necessary weight 95 being furnished by an ordinary inexpensive sad-iron such as is in use in every household.

The heater herein described is preferably made of such dimensions that it will be susceptible of receiving various sizes and 100 weights of sad-irons in order that the user of the heater may at will perform ironing operations with different degrees of weight.

I claim:

1. An electrical heater provided with 105 means for the attachment thereto of an ordinary sad-iron.
2. An electrical heater adapted to have an

ordinary sad-iron mounted thereon, and clamping means for securing an ordinary sad-iron to said heater, substantially as set forth.

3. The combination with an electrical heater, of binding rods surmounting said heater, a clamping bar fitted to said rods, and nuts on said binding rods for holding said

clamping bar; said binding rods and clamping bar being adapted to confine a sad-iron on said heater, substantially as set forth.

CHAS. VAN DYKE HILL.

In presence of

NELLIE V. ALEXANDER,
BLANCHE HOGAN.
